UNITED STATES PATENT OFFICE

JOHAN M. ANDERSEN, OF BROOKLINE, MASSACHUSETTS, ASSIGNOR TO ALBERT & J. M. ANDERSON MANUFACTURING COMPANY, OF BOSTON, MASSACHUSETTS, A CORPORATION OF MASSACHUSETTS

REWINDING MECHANISM FOR CLOCK SPRINGS

Application filed January 16, 1928. Serial No. 247,178.

This invention relates to a clock mechanism, and has for one of its objects to provide for rewinding the clock spring by an electric motor having a rotor, when the clock spring 5 has been unwound a predetermined amount, and for rendering the electric motor inoperative when the clock spring has been rewound a predetermined amount.

The invention among other uses is especially adapted to be embodied in a time circuit controller provided with a clock spring which is utilized as a motor for intermittently driving a rotatable member or device, and also used for driving the usual time train of 15 the clock.

One construction of time circuit controller of this character is shown and described in United States Patent No. 1,299,812 granted to me April 8, 1919.

20 The invention further has for its object to provide a novel mechanism for coupling one end of the clock spring with the rotatable device or member to be rotated thereby, and also with the rotor of the electric motor, whereby the spring may be unwound to intermittently operate the rotatable member and may be wound up by the electric motor in a continuous manner.

25 The invention also has for its object to provide a circuit controller for the electric motor which is operatively connected with the clock spring to cut in and cut out the electric motor as will be described.

30 The invention further embodies a novel construction of mechanism for controlling the operation of the rotatable member by the clock spring.

35 These and other features of this invention will be pointed out in the claims at the end of this specification.

Fig. 12, a detail to be referred to.

In the present instance, the invention is shown as embodied in a time circuit controller whose time element is substantially the 75 same as in the patent referred to and comprises a clock mechanism provided with a front plate a and with a back plate b , for supporting the operative parts of the apparatus.

The clock mechanism is provided with a 80 main spring 12 located in a barrel or drum 13 to which one end of the spring 12 is secured. The other end of the spring 12 is fastened to a main shaft 14 on which the barrel is loosely mounted. The barrel 13 85 as herein shown is provided at one end with a gear 15, and is closed at its opposite end by a gear 16 fast on the main shaft 14.

The rotation of the main shaft by the spring 12 is governed in the usual manner by 90 a time train of gears 17, provided with the usual escapement, not shown, and which is connected with the gear 16 by a pinion 18 on a shaft 19.

The shaft 14 has fast on it a time dial or 95 disk 20 provided with radial slots 21, with which co-operate bent fingers 22 on levers or arms 23, 24, which form with the disk 20 a selective mechanism for determining the time at which a rotatable member should open; 100

erate. The levers or arms 23, 24 are fast on concentric shafts or sleeves, not shown, but loosely mounted on the main shaft 14, so as to be engaged with the dial 20 at different points thereon, and, in the present instance, said levers or arms are provided with end portions 25, 26 (see Fig. 1), which extend beyond the bent fingers 22 and form tripping dogs or devices, being provided with inclined surfaces which co-operate with a beveled finger 28 on the arm 29 of a lever 30, fast on a shaft 31 extended through the front and back plates *a* *b* of the clock mechanism.

The lever 30 constitutes a release lever for the rotatable member or device, which in the present instance is a shaft 32, which is operatively connected with a member to be controlled by the apparatus. Such member may be an electric switch, gas cock or the like, not shown, but which is represented by the connecting rod 33. The rotatable device or shaft 32 is designed to be intermittently rotated by the clock spring 12, which also continuously drives the time train and the selective mechanism 20, 23, 24. The clock spring 12 is further designed to be automatically rewound intermittently by an electric motor 35.

To these ends the gear 15 driven by the clock spring 12 is connected with the shaft 32 and with the electric motor 35 by a coupling mechanism, preferably of a construction as will be described, which enables these results to be effected.

In the present instance, the coupling mechanism, shown in detail in Figs. 9 to 11 inclusive, consists of a shaft 40 having fast thereon by a pin 41 or otherwise a worm gear 42, and by a pin 43 a spur pinion 44, which is separated from the worm gear by a space in which is located a sleeve 45.

The sleeve 45 is loose on the shaft 40 and is provided at one end with a spur gear 46 and at its other end with a disk 47, having an annular flange or ring 48 of a width substantially equal to the width of the spur pinion 44 so that the latter may be within said flange.

The flange 48 is provided on its inner circumference with teeth 49, with which are adapted to mesh two spur pinions 50, 51 which also mesh with the spur pinion 44.

The pinions 50, 51 are loosely mounted on stud shafts 52, 53 carried by a disk 54 on a hub or sleeve 55, mounted loosely on the shaft 40 on the side of the pinion 44 opposite to the sleeve 45 thereon.

The sleeve 55 is provided at its opposite end with a spur gear 57, which meshes with a gear 58 mounted on a stud shaft 59 carried by the back plate *b* (see Fig. 2), the gear 58 meshing with the large gear 15, which may be designated the barrel gear.

The gear 46 on the sleeve 45 meshes with a gear 60 on the shaft 32.

The construction is such that when the shaft 40 is stationary, the sleeves 45, 55 are capable of being rotated as a differential unit on the shaft 40, in which case the pinions 50, 51 move about the center pinion 44 on the shaft 40, and are rotated on their stud shafts 52, 53 to produce rotation of the internally toothed flange 48 and its sleeve 45 at a different speed from the hub 55 but in the same direction. 70 75

When, however, the sleeve 45 is stationary and the shaft 40 is rotated, the sleeve 55 is capable of being turned at a different speed from the shaft 40, namely, at a much slower speed, because in this case the pinion 44 acts to turn the pinions 50, 51 on their shafts, and by reason of the pinions 50, 51 being in mesh with the internal teeth 49 of the now stationary flange 48, the disk 54 and its sleeve 55 are caused to turn on the shaft 40, thereby causing the gear 57 on the sleeve 55 to rotate the gear 58, which in turn rotates the barrel gear 15 to wind up the end of the clock spring 12 which is attached to the barrel 13. 80 85

The shaft 40 is operatively connected with the electric motor 35, which is fastened to the back plate *b*, and in the present instance this connection is effected by a pinion 61 on the shaft 161 of the armature or rotor of the electric motor 35 meshing with a gear 62 on a shaft 63, which has a worm 64 in mesh with the worm gear 42 on the shaft 40. The shaft 63 is supported by a hollow arm 65 extended from a metal casting or supporting wall 66, which is secured to the back plate *b* of the 100 clock frame.

It will thus be seen that under one condition of use, the clock spring 12 is coupled with the rotatable device or shaft 32 to rotate the latter by the unwinding of the end of the clock spring attached to the barrel 13, and under another condition of use, the clock spring is coupled with the rotor of the electric motor 35 to have its end attached to the barrel 13 wound up by said electric motor. 105 110

The clock spring 12 is designed when wound up to have sufficient power to operate the shaft 32 a number of times before the spring needs to be rewound, and therefore the electric motor is idle while the clock spring is intermittently operating the shaft 32 and the electric switch or other device connected therewith and not herein shown, but which is represented by the rod or bar 33. 115

The intermittent rotation of the shaft 32 by the clock spring 12 is controlled by the selective mechanism comprising the disk 20 and the levers 23, 24 co-operating therewith, which parts are continuously rotated by the unwinding of the end of the clock spring 12 connected with the main shaft 14 of the clock to which the disk 20 is secured to rotate therewith. 120 125

In the present instance, the shaft 32 is restrained from being rotated by the clock 130

spring, by a preferred construction of mechanism, which comprises two detent levers 70, 71, (see Fig. 5) and an arm 72 co-operating therewith. The detent levers 70, 71 are pivoted at 73 to the back plate *b* and are connected by links 74, 75 to a disk 76 at diametrically opposite points thereon, said disk being fast on the release shaft 31 and provided with a stud or pin 78, which extends through the disk and has its front end connected by a spring 79 to a stud 80 on the back plate. The rear end of the pin 78 is extended toward the back plate between two pins 81, 82 thereon (see Fig. 12) which serve as stops to limit movement of the disk 76 in opposite directions.

The disk 76 is turned in the direction of the arrow 83 (see Fig. 5) by rotation of the release shaft 31, and is turned in the opposite direction by the spring 79.

Movement of the disk 76 in the direction of the arrow 83 causes the link 74 to lift the detent lever 70 and remove it from the path of the arm 72, which will be hereinafter referred to as a stop arm for the shaft 32.

The same movement of the disk 76 causes the link 75 to lower the shorter detent lever 71 into the path of the arm 72 which is arrested thereby. This movement of the disk 76 is effected by one of the tripping devices 25 or 26 engaging the finger 28 on the release lever 30.

It may also be effected by the operator depressing the finger piece 84 on the arm 85 of said release lever 30.

When the tripping device 25 or 26 passes out of engagement with the finger 28 on the release lever 30, the disk 76 is turned in the direction opposite to that indicated by the arrow 83 by the spring 79, which elevates the detent lever 71 and lowers the detent lever 70. Elevation of the detent lever 71 releases the arm 72 and the gear 86 to which it is connected to move therewith as will be described, and allows the clock spring 12 to function as a spring motor and rotate the shaft 32 a half revolution and the gear 87 thereon a half revolution, which rotates the smaller gear 86 a full revolution.

The half revolution of the shaft 32 and its gear 87 moves the connecting bar 33 in the direction of the arrow 88, Fig. 5, to close the switch or other device connected therewith, or the switch may be arranged to be opened by such movement of the bar 33.

Let it be assumed that the movement of the connecting rod 33 in the direction of the arrow 88 closes the switch or device connected with the rod 33. On the next operation of the release lever 30, the shaft 32 and its gear 87 will be turned a second half revolution and the connecting bar 33 will be brought back into the position, shown in Fig. 5, thereby opening the switch or device connected with the bar 33.

It is designed that the clock spring 12 should have power enough when wound up to rotate the shaft 32 a number of times before its power has diminished to the point where it is unable to rotate the shaft 32 and operate the electric switch or other device connected with the said shaft.

While the clock spring 12 is being run down as described, the electric motor 35 is idle, and provision is made for cutting it into its circuit, when the clock spring has been unwound a predetermined amount, preferably before the said spring has been run down completely.

Provision is also made for cutting the electric motor 35 out of its circuit, when the clock spring has been rewound the proper or desired amount.

To these ends the circuit of the electric motor 35, represented by the wires 90, 91 in Fig. 1, is provided with a relatively small switch, which is operatively connected with the clock spring to be controlled thereby.

In the present instance, one construction of apparatus, which may be preferred, is shown for accomplishing these results.

The apparatus herein shown consists of a screw shaft 92 (see Figs. 3 and 4) which is supported at its rear end by the back plate *b* and has its front end extended into an internally threaded pinion 93, having a relatively long hollow hub 94 extended through and supported by the front plate *a*, the internal screw-threads of the pinion being extended into the hub 94 substantially the length thereof.

The pinion 93 meshes with the gear 16 which is fast on the main shaft 14 of the clock, and said pinion is relatively wide so that it can travel on the screw 92 and remain in mesh with the said gear.

The hollow hub 94 is provided at its outer end with a head 95 which has extended from its central portion a solid rod 96 of a length substantially equal to the distance the pinion 93 travels, said rod having at its end a head 97.

Between the heads 95, 97 is located a roller 98 on the upper end of a lever 99, having its pivot 100 mounted in arms 101 attached to a plate or bar 102 mounted on a base 103 of insulating material, which is secured to the front plate *a* of the clock.

The lever 99 has a relatively long hollow arm 104 (see Fig. 6) into which is extended the hollow arm 105 of a lever 106, which is pivoted at 107 to a lever 108, pivoted at 109 to lugs 110 on an arm 112 attached to the plate 102.

The lever 108 is provided with arms 113, 114 which co-operate with the arm 112 to limit the movement of the lever 108 in opposite directions.

The hollow arm 105 of the lever 106 is shorter than the hollow arm 104 of the lever 108.

29, and has located in it a helical spring 116, which is of sufficient length to engage the bottom of the hollow arm 104 and to be compressed thereby when the lever 106 is moved in opposite directions, as will be described.

10 The hollow arm 104 has extended from it laterally a bent finger 120 to which is pivotally secured one end of a link 121 of insulating material, which has a slot 122 into which is extended a pin 123 on the movable blade 124 of the switch for the electric motor 35.

15 The blade 124 is pivoted to a bracket 125 attached to the insulating base 103, and has its free end co-operating with the stationary contact members 126 attached to the base 103.

20 The bracket 125 constitutes one terminal for the motor switch and has one circuit wire 90 connected therewith (see Fig. 1) while the contact members 126 constitute the other terminal of the motor switch and the other wire 91 of the circuit is connected therewith.

25 By reference to Fig. 6, it will be seen that the levers 99, 108 constitute a toggle, which is connected with the switch member or blade 124 by the pin and slot connection 123, 122, which permits the blade to be opened and closed with a snap, when the spring 116 has been compressed the proper amount by the movements of the lever 99 in opposite directions.

30 In this manner a quick opening and closing switch for the electric motor 35 is provided.

35 In the open position of the motor switch blade 124 shown in Fig. 6, the center pin 107 of the toggle levers 99, 108 is on one side of a plane passing through the pivots 100, 109 for said levers, and in the closed position of said switch blade, represented in Figs. 2 and 3, the center pin 107 is on the opposite side of said plane.

40 The toggle levers 99, 108 are moved into the first of these two positions by the head 97 assisted by the spring 116, and into the second position by the head 95 assisted by the said spring.

45 The head 97 being attached to the hub 94 of the pinion 93 is moved with the latter as said pinion is reciprocated in the screw shaft 92. In Figs. 2 and 3, the electric motor switch 124 is shown closed and the motor 35 is rewinding the clock spring 12, as indicated in Fig. 8, through the worm 64, worm gear 42, shaft 40, pinion 44, pinions 50, 51, disk 54, gears 57, 58 and barrel gear 15.

50 The barrel gear 15 meshes with a gear 130 (see Figs. 8, 4, 7 and 8), which is fast on the screw shaft 92, so that as the barrel gear 15 is rotated to rewind the clock spring 12, the screw shaft 92 is rotated in such direction as to cause the pinion 93 to travel thereon in the direction of arrow 131 from substantially the position shown in Fig. 3 to substantially that shown in Fig. 4.

55 At or about the time the clock spring 12

has been rewound the desired amount, the head 97 movable with the pinion 93 engages the roller 98 and turns the toggle levers 99, 108 from the position shown in Figs. 2 and 3, into that shown in Figs. 4 and 6, thereby 70 opening the circuit of the electric motor 35.

It will thus be seen that the switch 124, 126 for the electric motor 35 is opened, when the clock spring 12 has been rewound the proper or desired amount, and at such time 75 the pinion 93 is in proximity to the back plate *b*, as represented in Fig. 4.

When the electric motor 35 has been cut out of circuit, it ceases to rotate the barrel gear 15, and the latter is then placed under the influence of the clock spring 12, which then functions as a motor to rotate the shaft 32 and operate the circuit controller, represented by the bar 33, when permitted so to do by the selective mechanism 20, 23, 24 releasing the stop arm 72 as above described.

At each intermittent operation of the shaft 32 by the clock spring functioning as a motor, the barrel gear 15 rotates the gear 130 and its screw shaft 92 in the proper direction to cause the pinion 93 to travel on the screw shaft 92 in a direction opposite to that indicated by the arrow 131, or toward the front plate *a* as herein shown.

It will thus be seen that the pinion 93 is 95 moved step by step in one direction by the clock spring when the latter is unwinding and functions as a motor to intermittently rotate the shaft 32, and is moved continuously in the opposite direction when it is being rewound by the electric motor.

At or about the time the clock spring has been unwound the predetermined or desired amount, the motor switch member 124 is moved into its closed position, shown in Figs. 2 and 3, to cut in the electric motor 35, and this is effected by the head 95 on the hub 94 of the pinion 93, engaging the roller 98 and moving the toggle levers 99, 108 from the position shown in Figs. 4 and 6, to that shown in Figs. 2 and 3.

The pinion 93 is also rotated continuously by the gear 16, which is continuously driven by the end of the clock spring attached to the main shaft 14 of the clock.

100 The rotation of the pinion 93 by the gear 16 effects movement thereof lengthwise on the screw shaft 92 in the same direction it is moved by the spring motor 12; that is in the direction opposite to that indicated by the arrow 131, so that the pinion 93 responds to the unwinding of both ends of the clock spring, one end of said spring being unwound intermittently and the other end being unwound continuously.

105 The continuous unwinding of one end of the clock spring also operates the time train 17 and the selective mechanism 20, 23, 24, and the intermittent unwinding of the other end operates the screw shaft 92.

The continuous rotation of the pinion 93 does not interfere with the longitudinal movement thereof in the direction of the arrow 131 by the rotation of the screw shaft 92.

5 The operation of the apparatus herein shown may be readily understood from the above description, but it will be briefly described as follows:

As represented in Fig. 1, the arms 23, 24 10 of the selective mechanism are engaged with the slots 21 on the disk 20 corresponding to the hours 5 P. M. and 6:45 A. M. and the time dial or disk 20 is rotated continuously by the end of the clock spring 12 attached to 15 the main shaft 14 of the clock. The selective mechanism is thus set to release the shaft 32 at 5 P. M. and again at 6:45 A. M., which is effected by the arms 25, 26 tripping the release lever 29, which operates the detent 20 levers 70, 71 to release the stop arm 72 and thereby release the shaft 32.

The end of the clock spring 12 attached to the barrel 13 rotates the shaft 32 a half turn and moves the bar 33 to close and open the 25 circuit controlled by the switch represented by the bar 33.

This rotation of the shaft 32 is effected by rotation of the coupling members 45, 55 as a differential unit upon the shaft 40, which 30 latter is at this time stationary, being held from rotating by the rotor of the electric motor 35, acting through the now stationary worm gear 42, worm 64, gear 62 and pinion 61 on the rotor shaft 161.

35 The clock spring 12 is designed to be able to rotate the shaft 32 a number of times before it is necessary to rewind it, and preferably the spring 12 will possess enough power to operate the shaft 32 and the switch connected 40 therewith a number of days before it requires to be rewound.

Let it be supposed that the spring 12 will function as a motor for rotating the shaft 32 for six days. At the end of this time, the 45 electric motor 35 will be cut into its circuit by its switch member 124, which is closed as above described by the pinion 93 when the latter reaches substantially the position represented in Fig. 3.

50 The electric motor 35 will now rotate the barrel 13 so as to rewind the clock spring, being connected with the barrel gear 15 through the coupling member 55 and its gear 57.

55 The other coupling member 45 is not driven by the electric motor, but is held stationary by being connected through the gears 46, 60 with the shaft 32, which is held by the detent lever 70 engaging the stop arm 72.

60 When the clock spring 12 has been rewound, the electric motor 35 is cut out of circuit as above described.

It will be observed that when the shaft 32 is rotated by the clock spring through the 65 barrel gear 15, the gears 46, 57 of the cou-

pling members are rotated rapidly in the same direction at different speeds, and when the barrel gear 15 is rotated in the opposite direction by the electric motor, the gear 57 of the coupling member is rotated at a different speed, and therefore said coupling members may be designated a differential gearing.

70 By means of this differential gearing between the spring motor and the electric motor, the spring motor 12 can function as a driver for rotating the shaft 32, while it is being wound up by the electric motor.

75 This enables the shaft 32 and the parts actuated by it to be operated if the selective mechanism should release the shaft 32 while the electric motor is in circuit and operatively connected with the clock spring.

80 Under these circumstances, the sleeve members 45, 55 are rotated as a differential 85 unit by the clock spring, while the shaft 40 and its pinion 44 are rotated by the electric motor.

85 As soon as the shaft 32 is rendered stationary by the detent lever 70 engaging the stop arm 72, the clock spring ceases to function as a driver and its rewinding by the electric motor is resumed.

90 The blow of the stop arm 72 against the detent lever 70 is cushioned by springs 150, 151 attached to fixed pins 152, 153 on the gear 86 and to pins 154, 155 on the stop arm 72 and extended through and movable in slots 156, 157 in said gear.

95 One embodiment of the invention is herein shown, but it is not desired to limit the invention to the particular construction shown.

100 What is claimed is:

1. In an apparatus of the character described, in combination, a clock mechanism provided with a main shaft and with a main spring having one end connected with said main shaft, a time train geared to said main shaft and governing rotation thereof, a gear loose on said main shaft and with which the other end of said main spring is connected to be driven by said main spring, a rotatable device, a differential having a member 105 geared with said rotatable device and a second member geared to the gear loose on said main shaft, a shaft upon which said differential members are mounted, an electric motor geared with the last-mentioned shaft, means for restraining said main spring from 110 rotating said device, means for releasing said restraining means, a selective mechanism driven by said main shaft and co-operating with said releasing means, a circuit controller for said electric motor, and means actuated by said main spring for automatically 115 operating said circuit controller to cut out the electric motor when the main spring has been wound up a predetermined amount and to cut in said electric motor when the 120

125

130

main spring has been unwound a predetermined amount.

2. In an apparatus of the character described, in combination, a clock mechanism provided with a main shaft and with a main spring having one end connected with said main shaft, a time train geared to said main shaft and governing rotation thereof, a gear loose on said main shaft and with which the other end of said main spring is connected to be driven by said main spring, a rotatable device, a differential having a member geared with said rotatable device and a second member geared to the gear loose on said main shaft, a shaft upon which said differential members are loosely mounted, gearing for connecting said differential members to enable them to be rotated as a unit by said main spring and operate said rotatable device, and for enabling the differential member geared with the gear loose on the main shaft to be rotated while the other differential member is stationary, and an electric motor geared with the shaft on which the differential members are loosely mounted for rewinding the main spring through one of the differential members while the other differential member is stationary.

3. In an apparatus of the character described, in combination, a clock mechanism provided with a main shaft and with a main spring having one end connected with said main shaft, a time train geared to said main shaft and governing rotation thereof, a gear loose on said main shaft and with which the other end of said main spring is connected to be driven by said main spring, a rotatable device, a differential interposed between the rotatable device and said main spring and having members geared to the rotatable device and the gear loose on said main shaft and movable as a unit by the end of the main spring connected with said loose gear to operate the rotatable device, a motor-driven shaft upon which said differential members are loosely mounted, gearing connecting said motor-driven shaft with the differential member geared with the end of the main spring connected with said loose gear to rotate said differential member, and wind up the main spring while the other differential member is stationary, and an electric motor for rotating said motor-driven shaft.

In testimony whereof, I have signed my name to this specification.

JOHAN M. ANDERSEN.
